UNITED STATES PATENT OFFICE.

PHILIP GOLINKO, OF NEW YORK, N. Y.

DESIGN FOR A SKIRT.

Application filed September 15, 1928. Serial No. 28,162. Term of patent 3½ years.

To all whom it may concern:

Be it known that I, PHILIP GOLINKO, a citizen of the United States of America, residing at New York city, county and State of New York, have invented a new, original, and ornamental Design for a Skirt, of which the following is a specification, reference being had to the accompanying drawing, forming part hereof, in which Figure 1 illustrates a front view of a skirt showing my new design, and Figure 2 is a rear view thereof.

I claim:

The ornamental design for a skirt as shown.

Signed at New York city, New York, this 13th day of September, 1928.

PHILIP GOLINKO.
